ABRADING

Charles H. Kasch, Davenport, Iowa, assignor to
H. C. Simmons, Davenport, Iowa

Application December 29, 1938, Serial No. 248,167

22 Claims. (CL. 51—90)

The present invention relates to a machine for making circular bevels or bevels on the arc of a circle, and more particularly to a machine for making scalloped-edge blades, such, for instance, as the blades of a bread-slicing machine.

This invention further relates to a method of grinding circular bevels, which method is particularly adapted to the grinding of scalloped-edge blades.

In grinding scalloped-edge blades, it has been customary to bend the blade about a cylindrical forming member and grind off a facette in the curved position. This practice is not particularly satisfactory since the bend in positions close to the end of a blade will not be the same as at positions removed from the end. When the curved bevel is produced in this manner, slight differences in the curvature of the blade will produce substantial variations in the size of the scallops. This prior method, furthermore, limits both the hardness of the steel which is employed and the size of the scallops. Thus, very hard steels which would make excellent blades can not be employed since bending even to a large radius of curvature, as employed for large scallops, would break such a steel blade. With the milder steels, such as are of necessity commonly employed, only the larger scallops may be produced, since bending to the small radius of curvature, as would be necessary, would result in breaking or permanently bending such a blade. Steel sufficiently mild that small scallops can be formed therein by this prior method would produce only inferior blades.

In accordance with the present invention, bevels, as above described, are produced by grinding with a grinding wheel which is rotated on an axis therethrough and revolved about an axis perpendicular to the surface of the work-piece about the center of curvature of the circular bevel or scallop to be produced. Following this grinding, the work and the grinding tool are relatively moved to present a fresh working surface, and the grinding step repeated.

In the case of grinding scalloped-edge blades, the grinding of any one scallop is completed while the wheel is revolved only part of the way about the center of curvature. During a part of the remaining time, i. e., while the wheel completes its revolution, the tool and the blade are moved relatively a distance in accord with the size of scallops being cut which will place the tool in position to grind the next scallop. The wheel is constantly revolved about the axis in

the following cycle; first, movement into engagement with the work-piece, second, grinding a circular bevel, third, movement out of engagement with the work-piece, and fourth, movement to the first position. During the fourth stage of the cycle, the axis of revolution is moved with respect to the work-piece to the next desired position. By this method of blade-grinding, blades of exceptionally hard steel may be produced, inasmuch as the blades are not bent during manufacture.

The machine shown in the accompanying drawings illustrates a machine in accord with the present invention and for performing the above described process. It should be understood that my invention comprises not only the specific machine hereinafter described and shown in the drawings but also the combinations of parts defined in the subjoined claims. In the drawings:

Fig. 1 is a plan of a machine in accordance with this invention and which is particularly adapted to the manufacture of relatively short bread-slicing blades;

Fig. 2 is a front elevation of the machine shown in Fig. 1;

Fig. 3 is a section substantially on the line 3—3 in Fig. 1;

Fig. 4 is a left end elevation of the machine with portions of the left frame plate broken away better to show the carriage structure;

Fig. 5 is a right end elevation;

Fig. 6 is a partial vertical section through the grinder head;

Fig. 7 is a bottom plan of the grinder head;

Fig. 8 is a section on line 8—8 in Fig. 4;

Fig. 9 is a plan of the work-holder with the pivot supports thereof shown in section; and

Figs. 10, 11, and 12 are sections on the lines 10—10, 11—11, and 12—12, respectively, in Fig. 9.

The machine shown in the accompanying drawings has a base 1 provided at each end with a vertical frame member 2, 3 between which extend a plurality of frame rods 4, 5, 6. A carriage 7, which includes the grinding head 8, is mounted to slide on the rods 5 and 6. The machine also comprises a blade-holder assembly 9, the details of which are shown in Figs. 9 to 12.

Referring now more particularly to Figs. 1, 3, and 4, the carriage 7 comprises a main carriage frame member 10 to which a motor-carrying plate 11 is pivoted at 12. The plate 11 is provided with a slot 14 which cooperates with a bolt 15 in an arm 16 of the member 10 for adjustment of the motor plate 11 about pivot 12.

toward and from member 10. The motor 17, which is attached to motor plate 11, provides the sole source of power in the machine both for traversing the carriage and for effecting grinding action on the work.

The motor 17 is provided with a pulley 18 which lies in the same plane as pulley 19 which the pulley 18 drives through a belt 20. The pulley 19 and also a pulley 22 are keyed to a tubular shaft 21, the pulley 22 being arranged to drive a pulley 23 through a belt 24. The pulley 23 is keyed to a sleeve integral with the gear 25 which is freely rotatable on sleeve 26 on adjusting arm 27. The adjusting arm has a ring 28 which slides readily about flange 29 on the carriage frame 10. A bolt 30 passes through the sleeve 26 and is movable in an arcuate slot in the carriage, the center of curvature of the slot being the same as of the flange 29. The gear 25 meshes with a gear 31 which is carried by a bearing 32 within the flange 29 and concentric therewith whereby, when belt 24 is tightened by moving the adjusting arm 27, the gears 25 and 31 remain in mesh. The above described train from the pulley 18 through the gear 31, during the normal operation of the machine, is constantly driven by the motor 17.

A clutch shaft 33 has a keyway most of its length and is mounted for rotation in frame plates 2 and 3. A bracket 34 is mounted on carriage frame 10 and is provided with a pair of arms 35 through each of which the clutch shaft 33 passes. A clutch arm 36 is positioned between the arms 35 and is keyed to shaft 33 for sliding movement therewith as a portion of the carriage 35 and for rotation therewith when the shaft is rotated by control means hereinafter described and shown in detail in Fig. 5. The end of the clutch arm 36 remote from shaft 33 is positioned below and in the axial line of the gear 31.

40 A tubular shaft 37 extends through the gear 31 and is freely rotatable therein. At the lower end of the shaft 37 and integral therewith is a pinion 38 between which and the carriage frame a thrust bearing is positioned. An external clutch plate 39 is slidably keyed to the upper end of shaft 37 and in lowered position engages an internal clutch face in the gear 31. The clutch plate 39 is rigidly secured to clutch rod 40, which is slidable in the shaft 37, by a cap 41 which screw-threadedly 45 engages both plate 39 and rod 40. A spring 42 is positioned about rod 40 between the pinion 38 and a pair of adjusting nuts 43 on the rod. The lower end of rod 40 has a plate 44 for engagement with clutch arm 36.

55 This construction allows the tubular shaft 37 to be spring-pressed upwardly in all positions of the clutch, and the clutch to be held normally in engagement by adjustable spring pressure.

The grinding head assembly 8 is supported by 60 a pair of bearings 45, 46 carried by the carriage frame 10, the tubular shaft 21 heretofore mentioned being carried by the bearing 45, and the head plate 47 being carried by the bearing 46. A third bearing 48 about the lower end of shaft 21 65 cooperates with plate 47 to hold the shaft and plate relatively concentric. The shaft 21, together with its drive plate 49 which is secured to the lower end thereof, and the head plate 47 may each be rotated independently of the other. A 70 ring gear 50 is secured to and completely encompasses the head plate 47 in a position to engage at all times the pinion 38. Normally, except when work is being positioned in or removed from the work-holder assembly 9, the clutch is in engagement, wherefore the head plate is normally

5 constantly rotated during operation and is stopped only for reloading the work-holder. It will be seen from an inspection of the driving train that the head plate 47 and the drive plate 49 are rotated in the same direction but at different speeds, the latter being rotated much faster than the former. Rotation in the same direction, however, is not necessary as any relative rotation of these two will effect rotation of the grinding wheel.

10 In order to lubricate the bearings 45, 46, and 48, an opening is formed in the tubular part of carriage frame 10 between the bearings 45 and 46 in which the plug 51 fits screw-threadedly. An oil deflector 52 is placed on the tubular shaft. To confine the oil, grease retainers 53 are positioned between pulley 22 and the carriage frame 10, between the head plate 47 and the carriage frame 10, and between the head plate 47 and the drive plate 49.

15 Referring now most particularly to Figs. 6 and 7, a guide plate 54 is secured as by bolts to the lower surface of the head plate 47, and is provided with a pair of guide channels 55, 56. A slide 57 is arranged to move in the guide channels, and to be clamped in adjusted position by a clamp bar 58 in channel 56 (see Fig. 3). The cooperating faces of the guide channels and of the slide are inclined inwardly and downwardly, whereby tightening of the clamp bar under action of set screws 59 will hold the slide firmly to the lower surface of the guide plate. An arm 60 on the slide has a bolt 61 affixed therein parallel to the direction of the guides 55, 56. This bolt 61 is arranged to pass through a pair of lugs 62 on the guide plate with a thumb nut 63 on the bolt between the lugs. With clamp bar 58 in open position, fine adjustment of slide 57 may be attained by turning the thumb nut, which adjustment may then be retained by setting the clamp 20 bar.

25 A shaft 64 is supported for rotation by a pair of bearings 65, 66 carried by the slide 57, the exposed portion of the shaft between the bearings being knurled. This shaft 64 is so positioned that in all adjustments of the slide 57 the axis of the shaft 64 intersects the axis of tubular shaft 21, and so that adjustment of the slide moves the shaft 64 toward and from said shaft 21. The shaft 64 is angularly related to the plate 54 so 30 that the inner end of the shaft upon which the abrasive wheel 67 is secured is lower than the outer end.

35 Immediately above the shaft 64, a stub shaft 68 is supported by the slide, the shaft 68 screw-threadedly engaging the slide and being provided with a nut to lock the shaft in adjusted position. The outer end of the stub shaft is provided with a bearing 69 upon the outer portion of which is clamped a drive wheel 70 which may be rubber 40 covered. The shaft 68 and drive wheel 70 are so related to the shaft 64 and drive plate 49 that the wheel is driven by the plate and in turn drives the shaft 64. Thus the wheel 70 may be positioned substantially midway between and in contact with both the plate and the shaft. Relative rotation of drive plate 49 and head plate 47 results in rotation of the drive wheel 70 and in turn in rotation of shaft 64 and the abrasive wheel 67 carried thereby.

45 With the structure described heretofore with a blade in the blade-holder 9 and the clutch 10 in engagement, the grinder head will be continuously rotated, resulting in revolution of the rotating abrasive wheel about and perpendicular 50

to the axis of rotation of the grinding head. When the shaft 64 passes above the work-holding clamp 9, the wheel 67 will, if the slide is properly adjusted, grind a single scallop in the edge of the work. Adjustment of slide 57 by the thumb nut 63 will vary the size of the scallop cut in the work. During the remainder of rotation of the grinding head, no grinding is effected and the wheel 67 is spaced from the work. During this latter period, the carriage assembly is indexed, by means presently described, to a position for grinding the next scallop.

The lower two-thirds of the periphery of the head plate 47 is primarily a plain cylinder, but is provided with a gear segment 72 extending partially around the lower third and with a similar gear segment 73 partially around the middle third, positioned diametrically of segment 72. A gear 74 is mounted on a vertically movable shaft, to which is also secured a gear 75, whereby the gears 74 and 75 are constrained to rotate and translate in unison. This pair of gears is mounted for vertical movement in the carriage frame, at a position such that a long tooth 76 of gear 74 rides on the cylindrical portion of the head and prevents turning of the gear 74 except when the ordinary teeth of gear 74 are in engagement with one or the other of the gear segments 72, 73. When the gear 74 engages either segment, the gear is given one complete revolution, after which tooth 76 again rides on the cylindrical portion of the head. Thus the gear 74 is a so-called intermittent gear, producing intermittent rotation in either of its positions of adjustment.

In the lower position of the gear 75, it engages a gear 77 fixed on a shaft, to which the gear 78 and the bevel gear 79 are also fixed, so that the gears 77, 78, and 79 rotate as a unit. The gear 75 may be raised to a position midway in elevation between gears 77 and 78, in which position the gear 75 engages an idle gear 80 which is in engagement with the gear 78. Movement of gear 75 from lower position to upper position, due to changing from direct drive to drive through the idle gear 80, results in reversal in the direction of rotation of gear 79. The gears 74, 75, 77, 78, and 80 are so related that when the tooth 76 is in engagement with the cylindrical portion of the head, the gear 75 may readily be moved from engagement with either gear 77 or gear 80 to engage with the other, i. e., in the described position, the teeth of gear 75 will be in alignment with the spaces between the teeth of the gear 77 or 80 with which it is not engaged. Gear 79 engages and rotates a second bevel gear 81 which is non-rotatably attached by a shaft to the bevel gear 82. The bevel gear 82 engages another bevel gear 83 which is fixed to an internally screw-threaded sleeve 84 rotatably carried by the carriage frame plate 10 (see Fig. 8). The sleeve 84 is in engagement with the lead screw 85 fixed in the frame of the machine, whereby rotation of the sleeve 84, effected by rotation of gear 74 through the described gear train, effects movement of the carriage along the machine. As the gear 74 is driven intermittently by the gear sectors 72 and 73, it will be seen this structure periodically indexes the carriage. This indexing occurs between grinding periods of the machine cycle.

Now, therefore, assuming the machine to be in the position shown in Figs. 2, 3, and 4, the clutch being in engagement, the grinding head will rotate clockwise in plan. After rotating through

a small arc, the grinding wheel will engage the work and upon further rotation cut a scallop from the work-piece, after which further rotation of the head disengages the wheel from the work. Subsequently thereto and prior to reengagement of the wheel with the work, the gear sector 72 engages the gear 74 and indexes the carriage to the right to position for grinding the next scallop.

Considering now the mechanism for shifting the transmission heretofore described, the grinder head is provided with a cam 86 on its upper surface, located substantially above the slide mechanism. An arm 87, provided with a cam roller 88, is slidably keyed on shaft 89, the arm being so proportioned that when gear 75 is in lower position and the carriage indexes to the right, the cam roller 88 will lie in the path of the cam 86. When the carriage has been indexed to the right end of the machine, the cam and cam roller will turn the shaft 89 counterclockwise, as seen in Fig. 4. A pair of lugs 91 extend upwardly from the carriage frame plate 10 and are each provided with an opening through which the shaft 89 extends. An apertured lever 92 is positioned between lugs 91 and is slidably keyed to the shaft 89. This construction constrains the lever 92 to move along the shaft with the carriage. A link 93 is pivoted to the upper end of lever 92 and, at its other end, the link is pivoted adjustably in a slot to an arm of the lever 94, pivoted at 96 to the bracket 97 of the carriage frame 10. The other end of lever 94 is bifurcated and provided with pins 98 which extend into a groove in the shaft upon which the gears 74 and 75 are secured. To counterbalance the weight of this shaft and the gears, a weight 99 is secured to lever 94.

Actuation of cam roller 88 by reversing cam 86 effectuates movement of gear 75 from its lower position in which the machine indexes to the right to its raised position in which the machine indexes to the left.

To understand properly the timing of the indexing and reversing operations, it should be noted that when indexing to the right the scallops are formed in the forward edge of the blade, and upon reversing, the blade-holder and blade are pivoted about axis 100 so that the blade is positioned forwardly of the grinding wheel and is ground on its then rear edge. Considering now the question of timing, starting from the position shown in Figs. 2, 3, and 4, after the head turns a short distance, say about 30°, with tooth 76 on space b, the grinding operation commences and then lasts for about 120°. During this 120°, the tooth 76 passes along the blank space adjacent the sector 73. Thereafter, for about 60°, the tooth 76 rides on blank space a (see Fig. 7), during which no grinding occurs. During the third stage, the sector 72 engages the gear 74 and indexes. During the fourth stage, the gear 74 rides on the blank space b for about 60°, passing the initial position and repeating the cycle of operation. When the last scallop during indexing to the right has been cut and tooth 76 is riding on space a, the cam 86 engages cam roller 88, shifting gear 74 to raised position and turning the blank holder about axis 100, by means hereinafter described. Due to shifting of the gear, instead of indexing being effected by sector gear 72, the gear rides on the blank space beside sector 72, during which the right hand scallop is ground on the back side of the work. Following this, tooth 76 rides on space b for about 75

60°, followed by the grinding stage of the cycle.

To shift the gear 74 when the carriage reaches the left extremity of its movement, a sleeve 101 is revolvably mounted on shaft 102, and is provided with a pair of lever arms 103 and 104. Arm 103 extends downwardly and rearwardly and is provided at its lower end with a cam roller 105 positioned to be engaged and elevated by cam 86. An adjustable link 106 is pivoted at one end to the upper end of arm 104 and at its other end to the upper end of lever arm 107 keyed to shaft 89. As viewed in Fig. 4, when the cam 86 elevates roller 105, the levers 103, 104, 107, and 94 are turned clockwise thereby depressing the gear 74 and placing the machine in position for right hand indexing.

The work-holder involves a clamp arranged to rotate on a bearing at each end thereof. Complemental pivot brackets 108 at each end are arranged to rotate in any suitable bearings 109 in frame members 2, 3 and are positioned so that the pivotal axis of the brackets intersects the axis of rotation of the grinder head. The main clamp element 110 is adjustably secured 20 to the brackets, as by bolts movable in slots in the brackets. A cooperating clamp member 111 is provided at each end with a pivot pin 112. The two clamp members 110 and 111 are pivotally secured together by fingers 113 having recesses 25 to receive pins 112 and which are secured to member 110. The edges of clamp members 110 and 111 rearward of pivotal axis 100 are spaced apart, and springs 114 are located therebetween so that the edges of the members adjacent axis 100 are 30 held firmly together. At the end of member 111, slots are provided in which manually actuatable cams 115 are pivoted on the pins 116, the cams operating against wear plates 117 in clamp member 110. A pair of spring guides 118 are adjustably secured by bolts in slots 119 with the unsecured ends thereof extending over the edge of the clamp. A pin 120 is secured to the end of each of the guides to engage in an opening in a blade blank to assist in the proper positioning 40 thereof in the clamp. As the clamp is considerably removed from the axial line 100, a pair of adjustable counterweights is secured to the brackets to counterbalance the clamp.

A gear 121 is keyed to a short section of shaft- 50 ing, which in turn is keyed in an opening in bracket 108 at the left of the machine so that turning of the gear turns the clamp. A lever 122 is keyed to shaft 89 and has an adjustable length link 123 pivoted thereto at a distance adjustable from the shaft 89. The opposite end of the link 123 is pivoted to operating arm 124 of sector gear 125 which engages gear 121. When shifting to right hand indexing, shaft 89 is turned clockwise, as shown in Fig. 4 as heretofore explained, resulting in clockwise movement 55 of the clamp assembly to the position shown in Fig. 3. When indexing is reversed to left hand indexing, the shaft 89, lever 122, and the clamp assembly turn counterclockwise, as viewed in 60 Fig. 4.

Brackets 108 are provided with stop arms 126 which cooperate with either of a pair of adjustable stops 127 to limit the movement of the clamp assembly in either direction; i. e., the stops do not allow the clamp assembly to be raised above a predetermined adjustable height 70 in either of its moved positions. In order to support the clamp assembly in the moved position and to avoid sagging of the clamp between its supports, supports 128, 129 are provided which 75

are carried by an arm 130 of the carriage. The support 128 is carried rearwardly of the support 129, the former supporting the clamp during right hand indexing and the latter during left hand indexing.

Each of the supports 128, 129 is pivoted to the arm 130, as at 131, 132, and is provided with stop arms 133 for cooperation with abutments 134 on arm 130. Each support is provided with an actuating arm 135 against which a spring-pressed plunger 136 acts to hold its respective support in normal vertical supporting position with the stop arm 133 against the abutment 134. By pressing either actuating arm 135 against the action of its plunger 136, the support is moved 15 away from position supporting the clamp, whereby the clamp may be turned to the other position thereof or turned to neutral position below the axis 100.

An actuator 138 is positioned near the right 20 hand end of the machine and in fixed longitudinal relationship with respect to the cam roller 88. The actuator is arranged to extend through opening 139 in the arm 130 and into contact with arm 135 to tilt support 128 out of supporting position. The cam roller 88 and actuator 138 are so related that the support 128 is removed from supporting position prior to actuation of the reversing mechanism by the cam roller 88. A second actuator 140 is fixedly secured to the 30 frame member 3 and extends into position to actuate arm 135 and turn support 129 out of normal position just prior to actuation of cam roller 105. While it is necessary for an actuator to move one of the supports out of normal position in order to move the clamp from supporting position, the clamp can move to either supported position directly, the clamp moving the respective support against the action of its plunger, and the support snapping into normal position 35 when the clamp has reached proper position.

Referring now to the control mechanism, shown most particularly in Fig. 5 but also disclosed in Figs. 1 and 2, an arm 141 is clamped as by a bolt 142 through openings in a split sleeve on the end of arm 141 to a collar which is keyed to transmission shaft 89, which is turned when the index shifting gears are shifted. This structure allows arm 141 to reciprocate along shaft 89 in an adjustably fixed radial position with respect thereto. The arm 141 is positioned on the shaft 89 between two springs 143, 144, the spring 143 forcing the arm toward the frame plate 2 and being strong enough to overcome the force of spring 144 which is employed to prevent rattling of arm 141 in certain positions of the machine. The lower end of the arm 141 lies normally in the same plane as a trigger 145 pivoted at 146 and provided with a hook 147. A lever 148 is fixed to clutch shaft 33, one arm of the lever having 60 a shoulder 149 engageable with hook 147. In engaged position of the trigger hook 147 and shoulder 149, the shaft 33 is in position such that the clutch is in engagement. An adjustable pressure spring 150 is arranged to press against lever 65 148 and to turn the lever and clutch shaft clockwise, as viewed in Fig. 5, so that when the trigger is disengaged from the lever the clutch is moved to disengaged position. A rod 151 is provided with a shoulder 152 and a reduced end portion 70 153 which is arranged to slide in a rotatable apertured pin 154 in the lower end of lever 148. The opposite end of the rod 151 is pivoted on the pin 155 carried by a plate 156 which may be formed integral with the operating handle 157 75

pivoted at 158. The rod 151 is made of two parts to provide adjustment of the length between the pivot 155 and the shoulder 152.

A pair of arms 159, 160 is fixed to opposite ends 5 of a vertical shaft parallel to the frame plate 2, the arm 159 having a bifurcated end portion extending about shaft 89 between plate 2 and arm 141 whereby to reciprocate the arm against the action of spring 143, and the arm 160 being provided with a cam roller pivoted on a vertical axis. 10 A cam plate 161 is formed integral with the handle 157 and the plate 156, and is so formed that initial counterclockwise movement of the handle from the position shown in Fig. 5 initially 15 restricts in turning the arms 159, 160 clockwise, as seen in plan, which will in turn move arm 141 away from plate 2 and out of line with trigger 145. Upon further movement of handle 157, the cam plate 161 holds the arm 141 in moved position 20 and brings shoulder 152 into engagement with lever 148, then turning the lever 148 counterclockwise. The spring 162 turns the trigger 145 into position to hold lever 148 in its moved position.

25 Pulling the handle as above described will obviously, through the clutch shaft 33, set the machine in operation. As the clamp moves from neutral vertical position to the right indexing position of Fig. 3, the shaft 89 and arm 141 turn counterclockwise, as shown in Fig. 5. The arm 141 will then overlap trigger 145. The handle is then released and is moved to the normal position shown, by spring 163. When the machine reverses to left indexing, as described heretofore, 30 the arm 141 is turned clockwise and becomes disengaged from trigger 145. The arm 141 is so adjusted that, when the cam roller 105 is engaged by cam 86, the arm 141 is turned into edge-engagement with the trigger 145 and presses it sufficiently far that the trigger disengages from 35 the lever 148, which, under action of spring 150, stops the machine automatically.

A rod 164 is pivoted at 165 to the handle 157 and is provided with a shoulder 166 and means 40 to adjust the distance from the pivot to the shoulder. The reduced end portion 167 of rod 164 is arranged to slide in a sleeve pivoted in trigger 145. The rod is so adjusted that, if the handle is moved clockwise from the normal position 45 shown in Fig. 5, trigger 145 will release lever 148, stopping the machine. It should be noted that stoppage of the machine, either manually or automatically, stops the train which rotates the head and indexing thereof but that such 50 stoppage does not stop rotation of the grinding wheel. An adjustable stop 168 is provided to limit counterclockwise movement of the trigger.

A gear 166' is fixed to shaft 167' rotatably carried in the carriage frame plate 10 with the lower 55 end of the shaft in driving engagement with pump 168'. The gear 166' engages the constantly driven gear 31 whereby the pump is driven at all times that the grinding wheel is rotating. The inlet 169 of the pump depends therefrom and dips into a tank 170 supported on the base. 60 The outlet of the pump communicates through a gland 171 supported by a bracket 172 with a pipe 173 which passes through the hollow shaft 21 and is secured in guide plate 54. At the end 65 of pipe 173, a duct is provided in plate 54 communicating with a nozzle 174 which may be adjusted to direct liquid pumped from the tank 170 onto the grinding wheel.

With any given threaded shaft or lead screw 70 75 85, the center-to-center spacing of the scallops

is of necessity fixed, since the sleeve 84 is turned a fixed number of degrees per rotation of gear 74. Accordingly, shaft 85 is made easily removable whereby a substitute shaft and sleeve, having a different pitch thread, may be inserted. For removal of this shaft, the set screws 175 should be loosened and the nut 176 removed. The bushing 177 to which the shaft is keyed may be drawn out of the plate 2. The shaft is then moved to the right, removing both the washer 178 and the bushing 179. The shaft may then be withdrawn through the left frame plate 3. A different sleeve 84 may be inserted in the carriage frame and a matching shaft inserted.

As has been noted, the distance of the grinding wheel from the grinding head axis may be adjusted by turning the thumb nut 63 and fixing it in adjusted position by the set screws 59. This adjustment gives control over the radius of curvature of the individual scallops. With any given shaft 85, movement of the grinding wheel toward the center of revolution thereof will produce a blade having deeper scallops in proportion to their length; i. e., a blade having longer, more pointed teeth.

25 These two adjustments, the pitch of the thread of shaft 85 and the radius of revolution of the grinding wheel give complete control over the characteristics of the blade.

With blades having various center-to-center 30 size of scallop, the ground length of blade of necessity varies somewhat. Also, it may be desirable to produce blades of various length of identical tooth character. Accordingly, the cam roller 88 and the arm 138 are adjustable longitudinally of the machine. For this purpose, a lead screw 180 is rotatably carried in the lower portion of the machine and is provided at one end with a crank 181 and a lock nut 182. The screw 180 threadedly engages a support 183 provided with guide bushings engaging the shafts 89 and 102. This support carries the arm 87 and its cam roller, the operating arm 138, and also a gauging sleeve 184 which slides with support 183 on shaft 102. This shaft 102 is provided with a plurality of gauging scales corresponding with the indexing using the various threaded shafts 85. With any particular shaft 85 in the machine, the end of sleeve 184 may be set at any of the scale markings on the corresponding scale, 40 as shown in Fig. 1, and the machine will reverse after cutting the indicated number of scallops. To bring any of the various scales on shaft 102 in view, the shaft is made rotatable under action 45 of thumb nut 175.

50 For a better understanding of the machine, considerable description of the operation of various assemblies has above been given in connection with the description of each assembly. In order to avoid repetition and as the detail operation should now be understood, the following statements of operation are intended to coordinate the various statements of operation.

With the shaft 85 and the radius of revolution 55 of the grinding wheel adjusted to produce a blade of the desired characteristics, the hand wheel 181 is adjusted until the sleeve indicates the desired length of blade on the proper scale. The carriage is positioned, as shown in Fig. 1, and the arm 141 is adjusted so as to trip the trigger 145 60 when the clamp assembly is moved to neutral position under action of the left hand cam roller. The belts 20 and 24 are properly tensioned by adjustment of motor bracket 11 and belt tightener 27. The motor may then be started, thereby 65 70 75 80 85 90 95

rotating the grinding wheel, communicating power to the clutch, and driving the pump. A work-piece may then be inserted in the clamp.

The handle 157 may then be pulled forward, whereby the clutch is engaged, the work moved to grinding position, and grinding initiated. When the grinding has proceeded to the right end of the blade, as predetermined by the hand wheel 181, the machine automatically reverses, turning the blade over and moving it to the opposite side of the center of revolution. Due to the relation of grinding and indexing of right hand and left hand operation, above described, the first cut after reversal is made prior to indexing thereafter. While in describing the timing above, grinding through a 120° arc was indicated, this varies with the relation of the center-to-center distance of the scallops and the radius of revolution of the grinding wheel. Grinding on the second side then continues automatically until the blade is completed when the clutch is disengaged under action of the cam roller 105. The finished blade may then be removed from the machine. For producing more blades of the same variety, all that is necessary is to insert the work-piece, pull the handle and, when operation is complete, remove the blade.

Blades produced in accordance with this invention are far superior to the blades at present on the market. Thus, a common drawback of present blades is that the grinding is effected in a direction transverse to the length of the blade. This results in the friction between the blades and the bread being unduly great. Blades produced on the machine of this invention have the grain of the grind at all places parallel to the ground edge, thereby considerably reducing the friction and resulting in the drag of the blades on the bread being considerably less.

The blades produced in accordance with this invention are further characterized by their long, thin cutting points. Thus, these blades have a greater ground depth at the points than at the centers of the scallops, and a section of a blade transverse to the length of the blade through a cutting point shows that the points are hollow ground. On the other hand, a blade made by wrapping a blank into a cylinder and grinding facettes is characterized by relatively blunt points. These comparisons are on the basis of blades of the same size scallops and with the angles between ground surfaces at the middle of a scallop the same.

The above description is illustrative of the invention and is not to be taken as indicative of the scope thereof, the scope being defined by the claims appended hereto. While I have above described a machine in which the carriage is movable and a fixed length blade is ground on its opposite sides in a longitudinally fixed position, it is obvious that within the broad scope of this invention considerable latitude is encompassed within the scope thereof. Thus, for instance, the grinding head may be rotated on a fixed axis and the blade be indexed in response to rotation thereof and be automatically reversible and be provided with an automatic stop similar to that disclosed above. For grinding substantially continuous blade material, a pair of grinding heads in facing relation on opposite sides of the material may be employed, being driven synchronously and the material indexed step-by-step in response to movement of grinding heads when out of contact with the material. 75 In connection with the grinder head it is to be

noted that while the shaft of the abrasive wheel has been shown at an acute angle to the axis of revolution and the wheel shown as cylindrical the shaft may be at any angle, for instance, a right angle, and a truncated conical wheel employed. 5

Having now described my invention, I claim:

1. A machine for grinding scalloped bevel edges, comprising an abrading wheel, means for rotating said wheel, means for revolving said wheel about an axis substantially intersecting the axis of rotation of said wheel, means for positioning a work-piece with the portion to be ground substantially perpendicularly to the axis of revolution of said wheel and at a position 15 along said axis and spaced therefrom a distance such that the periphery of said wheel forms an arcuate bevel in the edge of said work-piece, and means for relatively indexing the wheel and said work-piece, said work-piece in the region of 20 grinding having the longitudinal extent thereof directed substantially tangentially of the orbit of said wheel, whereby to grind a series of arcuate bevels.

2. A machine for grinding scalloped bevel edges, comprising an abrading wheel, means for rotating said wheel, means for revolving said wheel about an axis substantially intersecting the axis of rotation of said wheel, means for positioning a work-piece with the portion to be 25 ground substantially perpendicularly to the axis of revolution of said wheel and at a position along said axis and spaced therefrom a distance such that the periphery of said wheel forms an arcuate bevel in the edge of said work-piece, 30 said work-piece in the region of grinding having the longitudinal extent thereof directed substantially tangentially of the orbit of said wheel, and means actuated by said means for revolving said wheel when said wheel is in a position of 35 40 its cycle in which it is out of contact with said work-piece for relatively indexing the wheel and said work-piece whereby to grind a series of arcuate bevels.

3. A machine for grinding curved bevels, comprising an abrading wheel, means for rotating said wheel, means for revolving said wheel about an axis substantially intersecting the axis of rotation of said wheel, means for relatively positioning a work-piece and said wheel so that the portion of the work-piece to be ground is substantially perpendicular to the axis of revolution and that said wheel is in contact with said work-piece, said work-piece in the region of grinding having the longitudinal extent thereof directed 45 50 55 substantially tangentially of the orbit of said wheel, with the grinding face of said wheel at an angle to said axis of revolution at the point of contact with said work, whereby an arcuate bevel is produced in said work-piece, and means actuated by the second named means for relatively indexing the work-piece and grinding wheel to a similar working position spaced along the work-piece.

4. A machine for grinding scalloped bevel edges, comprising an abrading wheel, means for rotating said wheel, means for revolving said wheel about an axis substantially intersecting the axis of rotation of said wheel, means for relatively positioning a work-piece and said 65 70 75 wheel so that the portion of the work-piece to be ground is substantially perpendicular to the axis of revolution of said wheel, with the grinding face of said wheel at an acute angle to the axis of revolution at a point of contact with 80 85 90 95 95 the work-piece.

said work, said work-piece in the region of grinding having the longitudinal extent thereof directed substantially tangentially of the orbit of said wheel, and means for relatively indexing said work and said wheel a distance less than the diameter of revolution of the grinding face at said point whereby to grind a series of intersecting scalloped bevels.

5. A machine for grinding bevel edges, an abrading wheel, means for rotating said wheel, means for revolving said wheel about an axis substantially intersecting the axis of rotation of said wheel, means to secure a work-piece in a position substantially perpendicularly to the axis of revolution of said wheel and to one side thereof and at a position therealong in which it is contacted by said wheel in the revolution thereof, and means to move said work-piece to a position on the opposite side of said axis substantially perpendicular thereto and in substantially the same plane, the work-piece being opposite sides up in said positions and equally spaced from the axis of revolution in both said positions.

6. A machine for grinding bevel edges, an abrading wheel, means for rotating said wheel, means for revolving said wheel, means to secure a work-piece in a position substantially perpendicularly to the axis of revolution of said wheel and to one side thereof and at a position therealong in which it is contacted by said wheel in the revolution thereof, means to move said work-piece to a corresponding position on the opposite side of the axis of revolution with the work-piece the other side up, means to relatively index the wheel and work-piece in the first mentioned position of the work-piece, and means to relatively index the wheel and work-piece in the second mentioned position of the work-piece to the same positions of the wheel along said work-piece as when in the first mentioned position.

7. In a machine of the character described, a tool, means rotatably mounted carrying said tool spaced from the axis of rotation, means to support a sheet material work-piece in a position operative with respect to said tool during a portion of the rotation of said means, and substantially perpendicular to the axis of rotation and at one side thereof, and means to move said work-piece to the complementary position on the opposite side of the axis, with the work-piece the other side up.

8. In a machine of the character described, a tool, means rotatably mounted carrying said tool spaced from the axis of rotation, means to support a sheet material work-piece in a position operative with respect to said tool during a portion of the rotation of said means, and substantially perpendicular to the axis of rotation and at one side thereof, means to move said work-piece to the complementary position on the opposite side of the axis, with the work-piece the other side up, indexing means timed with respect to the rotation of said means for indexing the carrying means relatively along the work-piece in accord with the cycle, related to rotation of said carrying means, as follows; operation by the tool, blank, index blank, repeating this cycle until the reversing cycle, as follows; operation by the tool, movement of the work-piece to the complementary position, operation by the tool, blank, index in the opposite direction, blank, then repeating the last four cycle periods.

9. In a machine of the character described, a frame, a carriage mounted for reciprocation on said frame, a tool head rotatably mounted on said

carriage, means normally constantly to rotate said head, cooperating means on said frame and carriage to effect reciprocation of the carriage, drive means on said carriage to effect limited actuation of said cooperating means, and cooperating means on said head and carriage for initiating operation of said drive means whereby reciprocation of said carriage is effected only in predetermined angular position of said head.

10. In a machine of the character described, a frame, a carriage mounted for reciprocation on said frame, a tool head rotatably mounted on said carriage, means normally constantly to rotate said head, cooperating means on said frame and carriage to effect reciprocation of the carriage, drive means on said carriage to effect limited actuation of said cooperating means on said head and carriage for initiating operation of said drive means whereby reciprocation in one direction of said carriage is effected only in predetermined angular position of said head, one of said cooperating means on said head and carriage being movable out of position to engage the other and into a position to engage an alternative cooperating means, said one of said cooperating means and said alternative means cooperating to effect reciprocation only in another predetermined angular position of said head.

11. In a machine of the character described, a tool-support arranged to rotate on an axis therethrough, a tool supported thereby in a position spaced from said axis for movement in a plane perpendicular to said axis of rotation, and a work-support for sheet material type of work arranged to position said work in tool-engaging position in a plane perpendicular to and at one side of said work, said work-support being mounted for rotation through an angle of about 180° on an axis intersecting the axis of rotation of said tool-support.

12. In a machine of the character described, a tool-support arranged to rotate on an axis therethrough, a tool supported thereby in a position spaced from said axis for movement in a plane perpendicular to said axis of rotation, a work-support for sheet material type of work arranged to position said work in tool-engaging position in a plane perpendicular to and at one side of said work, said work-support being mounted for rotation through an angle of about 180° on an axis intersecting the axis of rotation of said tool-support, and means for moving the tool-support step-by-step in a direction parallel to the axis of rotation of the work-support.

13. In a machine of the character described, a tool-support arranged to rotate on an axis therethrough, a tool supported thereby in a position spaced from said axis for movement in a plane perpendicular to said axis of rotation, a work-support for sheet material type of work arranged to position said work in tool-engaging position in a plane perpendicular to and to one side of said tool, said work-support being mounted for rotation through an angle of about 180° on an axis intersecting the axis of rotation of said tool-support, means for moving said tool-support along the axis of rotation of said work-support, and means under control of said tool-support for effecting said rotation of the work-support after a predetermined extent of movement along the axis, said last named means also shifting the means for moving to effect reversal of the direction of said relative movement.

14. In a machine of the class described, a frame, a work-support carried by said frame and

- arranged to oscillate through an arc of about 180° about an axis about which work supported thereby is revolved, a tool-support carried by the frame on the side of the plane defined by the 5 terminal positions of the work-support away from the direction in which the work-support oscillates, said work-support and tool-support being arranged relatively to reciprocate parallel to said axis along said work-support, and a pair of members 10 mounted on the carriage to move therewith and support the work-support in either of its terminal positions.
15. In a machine of the character described, a work-support arranged to oscillate through an arc of about 180° from one terminal position to another, a carriage, means on said carriage to effect indexing thereof along said support and toward one end of said support, reversing means 15 along the path of movement of said carriage in the direction of said end for engagement therewith for effecting reversal of the direction of indexing by said indexing means, an arm pivoted to said carriage in a position to support said work-support in one of said terminal positions, and 20 releasing means along the path of movement of said carriage in said direction positioned operative to release said arm prior to operation of said reversing means.
16. In a machine of the character described, a 25 frame, a carriage mounted for reciprocation in either direction on said frame, a tool-support mounted for rotation on said carriage, dual means for initiating each step of step-by-step reciprocation of the carriage mounted in spaced positions 30 axially with respect to said tool-support for rotation concurrently therewith, means mounted on said carriage shiftable from a position to be actuated by one of said dual means to a position to be actuated by the other of said dual 35 means for effecting reciprocation in one direction when actuated by one of said dual means and in the other direction when actuated by the other of said dual means.
17. In a machine of the character described, a 40 grinding head body member mounted for rotation about an axis therethrough, a drive plate mounted in said body member for rotation with relation to said body member about said axis, a shaft carried by said member at an angle to said 45 axis and a drive wheel in frictional engagement with said drive plate and in driving relation with said shaft, means for differentially rotating said member and said plate, and a grinding wheel mounted on said shaft.
- 50 18. The method of forming bevel scallop edges on sheet material work-pieces, comprising rotating a grinding wheel on its axis, continuously revolving said wheel about an axis external to said wheel, while rotating, said axis of revolution being so located that the wheel moves into and out of engagement with a sheet material work-piece which is positioned so that one edge thereof is substantially tangential to the orbit 55 of said wheel, whereby scallops are cut in said edge, the revolving of said wheel cyclically, first, moving said grinding wheel into grinding engagement with the work-piece, second, moving said wheel while in engagement in a circular path, third, moving said wheel out of engagement with the work-piece, and fourth, moving the wheel while out of engagement to the initial position of the first stage of the cycle, and relatively moving the axis of revolution and the 60 work-piece in a direction parallel to the plane 65

of the work-piece during the fourth stage of the cycle.

19. The method of forming bevel scallop edges on sheet material work-pieces, comprising rotating a grinding wheel on its axis, revolving said 5 grinding wheel about an axis substantially intersecting the axis of rotation while maintaining the angle between said axes constant, said axis of revolution being external to said wheel and so located that the wheel moves into and out of engagement with a sheet material work-piece which is positioned so that one edge thereof is substantially tangential to the orbit of said wheel, whereby scallops are cut in said edge, the revolving of said wheel cyclically, first, moving 15 said grinding wheel into grinding engagement with the work-piece, second, moving said wheel while in engagement in a circular path, third, moving said wheel out of engagement, and fourth, moving the wheel while out of engagement 20 to the position of the first stage of the cycle, and relatively moving the axis of revolution and the work-piece in a direction parallel to the plane of the work-piece during the fourth stage of the cycle. 25

20. A machine for grinding scalloped bevel edges comprising an abrading wheel, means for rotating said wheel, means for revolving said wheel about an axis substantially intersecting the axis of rotation of said wheel, and means for 30 relatively positioning a work-piece, having a substantially flat surface and an edge to be scallop ground, in a position with said surface substantially perpendicular to the axis of revolution of the wheel, with the edge to be ground substantially tangential to the orbit of the wheel, with the work-piece spaced along the axis of revolution so that the wheel engages the work-piece, and with the body of the work-piece, except for 35 the portion being ground, lying outside of the orbit of the wheel. 40

21. A machine for grinding scalloped bevel edges comprising an abrading wheel, means for rotating said wheel, means for revolving said wheel about an axis substantially intersecting the axis of rotation of said wheel, means for relatively positioning a work-piece, having a substantially flat surface and an edge to be scallop ground, in a position with said surface substantially perpendicular to the axis of revolution of the wheel, with the edge to be ground substantially tangential to the orbit of the wheel, with the work-piece spaced along the axis of revolution so that the wheel engages the work-piece, and with the body of the work-piece, except for 45 the portion being ground, lying outside of the orbit of the wheel, and means to relatively index the work-piece and the axis of revolution of said wheel to a position similar to the defined position, but in which the axis of revolution is 50 relatively spaced along the edge of the work-piece a distance such that the scallops ground in the edge of the blade in the two positions form intersecting surfaces on the surface of the work-piece. 55

22. A machine for grinding scalloped bevel edges comprising an abrading wheel, means for rotating said wheel, means for revolving said wheel about an axis substantially intersecting the axis of rotation of said wheel, means for 60 relatively positioning a work-piece, having a substantially flat surface and an edge to be scallop ground, in a position with said surface substantially perpendicular to the axis of revolution of the wheel, with the edge to be ground substantially 65

5 tially tangential to the orbit of the wheel, with the work-piece spaced along the axis of revolution so that the wheel engages the work-piece, and with the body of the work-piece, except for the portion being ground, lying outside of the orbit of the wheel, and automatic means, operative responsive to revolution of said abrading wheel through that portion of its orbit in which it is out of contact with said work-piece, to rela-

tively index the work-piece and the axis of revolution of said wheel to a position similar to the defined position, but in which the axis of revolution is relatively spaced along the edge of the work-piece a distance such that the scallops 5 ground in the edge of the blade in the two positions form intersecting surfaces on the surface of the work-piece.

CHARLES H. KASCH.
